UNITED STATES PATENT OFFICE.

CLARENCE B. HODGES, OF DETROIT, MICHIGAN:

FORCE-FEED LUBRICATOR.

No. 841,249.

Specification of Letters Patent.

Patented Jan. 15, 1907.

Application filed March 11, 1905. Serial No. 249,594.

To all whom it may concern:

Be it known that I, CLARENCE B. HODGES, a citizen of the United States, residing at Detroit, in the county of Wayne and State of Michigan, have invented certain new and useful Improvements in Force-Feed Lubricators, of which the following is a specification, reference being had therein to the accompanying drawings.

10 The invention relates to improvements in force-feed lubricators; and it consists in the construction of such a lubricator comprising a pump and valve mechanism for forcing the oil to the desired point.

15 The invention further consists in the construction of a valve mechanism whereby the usual check-valves are dispensed with, and, further, in a pump mechanism in which a single shaft acts as a valve-shaft and an aper-tured device for the pump, and, further, in the construction of a device in which a single pump takes the oil from the reservoir, passes it through a sight-feed device, and takes the oil from the sight-feed device and delivers it 25 to the point to be lubricated.

20 The invention further consists in the construction, arrangement, and combination of the various parts, as more fully hereinafter described, and particularly pointed out in 25 the claims.

30 In the drawings, Figure 1 is a vertical central cross-section through my improved lubricator. Fig. 2 is a vertical central section through Fig. 1. Fig. 3 is a cross-section on line 3-3, Fig. 2. Fig. 4 is a horizontal section centrally through the valve-shaft and showing the piston in elevation.

35 A represents the reservoir, which in this case contains the pump and valve mechanism. At the bottom of the reservoir and transversely thereof is a conical valve-casing B, in which is the conical valve B'. This valve has the shaft C, extending through one end, and to this shaft any suitable drive mechanism may be attached for rotating the 45 shaft.

40 C' is a piston working in a cylinder C'', formed longitudinally and axially of the valve. This piston I have shown in the 50 shape of a plain shaft which extends to the outside through the casing D, passing through an annular nut D', and at the outer end provided with the usual packing-gland D''. This piston is provided with a lug E, engaging in a slot E' in the extension F of the valve. Sleeved on the piston C' are the two

50 collars G and G', both these collars being held from movement and the shaft rotating therein. Between the two collars, the proximate faces of which are properly shaped, is a camway H, in which travel the roller-wrists I, which are fixed to the piston.

I' is a spring bearing at one end against the collar G' and at the other end against the end of a valve to hold the valve tightly to its seat.

55 At the inner end of the cylinder the valve is provided with a lateral port a. The valve-casing is provided with a port b, leading into the reservoir, and a final exit-passage c, through which the oil is delivered to the 60 point to be lubricated. Extending up from the valve-casing is a sight-feed passage d, the upper end of which connects into a transverse passage d' at the top of the reservoir. At the other end this passage is provided 65 with a spring-seated check-valve e, controlling the port leading back into the reservoir. From the passage d' is the nozzle h, which is adapted to discharge oil through the sight-feed chamber i, provided with the bull's-eye 70 glasses i'. At the bottom of the sight-feed chamber is the passage k, which leads back to the valve-casing. The passages d d', the nozzle h, the sight-feed chamber i', and the 75 return passage k I refer to as a "sight-feed" 80 passage, leading from and returning to the controlling-valve of the pump.

85 The oil passing from the passage d' through the nozzle is controlled by a needle-valve l, extending through the top of the reservoir 90 and adjustable by turning the valve-stem in the usual manner.

95 The device being thus constructed, the operation is as follows: Oil being supplied to the reservoir and motion being imparted to the shaft C, (or to the shaft C', if desired,) the valve B' will be rotated, and with it the piston C'. The port a in the valve will first register with the inlet-port b, and at this point the piston C' will be moved outwardly, so 100 that it will draw the oil from the reservoir into the cylinder. The valve then rotates to the position shown in Fig. 1, the port a registering with the passage d, and during this 105 registration the piston is moved inward, so as to force the oil drawn from the reservoir into the sight-feed passage. The port a in the continued rotation of the valve then registers with the return-passage k, and the piston is 110 again moved outward, drawing the oil from this sight-feed passage into the cylinder, and the valve then moves, with the port a regis-

tering with the discharge-passage *c*, and the piston is reversed in motion to discharge the oil to the point to be lubricated.

It will be seen that the single pump, with its single valve, is adapted to take the oil from the reservoir, discharge it through the sight-feed passage, so that the operator may know how much oil is being fed, and then take up again the oil thus pumped and deliver it out to the point to be lubricated.

In case the valve *l* is set so that less oil can pass therethrough than is pumped into the sight-feed passage, the surplus under pressure will lift the check-valve *e* from its seat and fall back into the reservoir to be pumped over again.

I may provide the device with any suitable gage-glass, such as shown at *M*, Fig. 2, and with a filling-aperture, as shown at *N*, Fig. 2.

20 The specific form of device here shown is but one embodiment of my invention, as it is obvious that it may be embodied in many different forms, as I believe in its broader phases my invention is quite generic as to 25 certain features of construction, which I have pointed out in the claims.

What I claim as my invention is—

1. In a lubricator, the combination of a rotary valve, a piston therein having means for causing the two to rotate together, and means for causing the valve to rotate and the piston to reciprocate.

2. In a lubricator, the combination of a rotary valve, a cylinder and piston concentrically arranged therein, means for causing the two to rotate together, means for imparting a rotary motion to one member, and means for reciprocating the piston by and during the rotation.

3. In a lubricator, a rotary valve having a longitudinally axially arranged cylinder therein, a piston in the cylinder rotating with the valve, means for rotating the valve, such rotation causing the reciprocation of the piston.

4. In a lubricator, a rotary valve having a longitudinally axially arranged piston therein, rotating therewith, and a drive connection device for rotating the valve and thereby reciprocating the piston.

5. In a lubricator, a reservoir, a pump, there being a sight-feed conduit leading from the pump and returning thereto, a discharge-conduit from the pump, and ports, and actuating means to cause the pump to receive a charge from the reservoir, force the same through the sight-feed conduit, and to again take the charge and discharge it to the point to be lubricated.

6. In a lubricator, a pump, having two discharge-conduits therefrom, one of said conduits comprising a sight-feed leading from and returning to the pump, the valve, and means for actuating the valve and pump to cause it to first discharge into the sight-feed

conduit, and then to discharge through the other discharge-conduit.

7. In a lubricator, the combination of a pump, a sight-feed conduit leading therefrom and returning thereto, a sight-feed device therein, an exit-conduit, a valve and actuating means for the pump, to cause it to first discharge into the sight-feed conduit and then to draw therefrom and discharge into the exit-conduit. 75

8. In a lubricating device, the combination of a pump, a rotary valve controlling the inlet and outlet of the pump, two supply and two discharge ports, and a single port in the valve adapted to connect with all the 85 ports in a single revolution; and means for reciprocating the pump to make two strokes to each rotation of the valve.

9. In a lubricating device, a reservoir, a rotary valve therein, an axially arranged cylinder in the valve, a piston therein, there being a port leading from the valve at the end of the cylinder, an inlet-port from the cylinder to the valve, a conduit including a sight-feed device, leading from and returning to the valve, and an exit-conduit, the port in the pump registering with the ports and conduits named, successively, and means for reciprocating the piston. 90

10. In a lubricating device, a reservoir, a valve-casing communicating therewith, a sight-feed conduit having both ends terminating in ports in the casing, an exit-port in the casing, a rotary valve controlling all the ports, and a pump adapted to draw oil from the reservoir, force it through the sight-feed conduit, and to draw the oil from the sight-feed conduit and discharge it through the exit-port. 95

11. In a lubricating device, a reservoir, a pump, a sight-feed conduit leading therefrom, a regulating-valve therein, an overflow-conduit therein, and connections whereby the said pump is alternately connected to discharge oil into and to take oil from said sight-feed conduit. 105

12. In a lubricating device, a reservoir, a pump, a sight-feed conduit leading therefrom and returning thereto, and valve connections whereby said pump is alternately connected to discharge oil into and take oil from said sight-feed conduit. 115

13. A lubricator comprising a valve controlling the inflow and outflow of the lubricant, and a pump having a plunger for actuating the valve and for drawing in the lubricant and forcing it out by way of the valve, the said plunger having a sliding connection with the valve. 120

14. A lubricator comprising a valve alternately connecting with a lubricant-supply and a lubricant-discharge leading to the part to be lubricated, a pump-cylinder, a plunger mounted to turn and to reciprocate in the cylinder and having a sliding connection with 130

- the said valve, to draw in the lubricant by way of the valve and to force it out through the valve and means for rotating and reciprocating the said plunger.
- 5 15. A lubricator comprising a cylinder terminating in a valve-seat, a plunger mounted to turn and to reciprocate in the said cylinder, and a valve on the said seat, adapted to alternately connect with a supply and with a discharge, the said valve being in communication with the said cylinder and the said valve having a sliding connection with the said plunger.
- 10 16. A lubricator comprising a cylinder terminating in a valve-seat, a plunger mounted to turn and to reciprocate in the said cylinder, a valve on the said seat, adapted to alternately be connected with a supply and with a discharge, the said valve being in communication with the said cylinder, and the said valve having a sliding connection with the said plunger and a spring pressing the valve, to hold the same to its seat.
- 15 17. A lubricator comprising a cylinder provided with a valve-seat, a plunger mounted to turn and to reciprocate in the said cylinder, a valve held on said valve-seat and having a sliding connection with the plunger, whereby the valve turns when the plunger is turned, the said valve being provided with
- a recess adapted to alternately connect with a supply and a discharge, the said recess in the valve communicating by a port with the interior of the cylinder, means for rotating 35 the plunger, and means for reciprocating the plunger when rotated.
- 20 18. In a lubricator, a pump, two valve-controlled inlet connections thereto and two valve-controlled discharge-conduits therefrom, and means for actuating the pump and the valve whereby said pump successively draws from the inlets and discharges into the outlets successively, and a sight-feed feature in one outlet-conduit. 40
- 25 19. In a lubricator, a pump, two inlet-conduits and two outlet-conduits, a rotary valve controlling all said conduits, and a sight-feed feature in one outlet-conduit. 45
- 30 20. In a lubricator, the combination of a pump, two separate discharge-conduits therefrom, a valve mechanism whereby the pump is caused to discharge successively into said conduits, and a sight-feed feature in one of said conduits. 50
- 35 55

In testimony whereof I affix my signature in presence of two witnesses.
